UNITED STATES PATENT OFFICE

MILLARD M. KENNEDY, OF EL PASO, TEXAS

ILLUMINATED SIGN

Application filed August 10, 1929. Serial No. 384,981.

This invention relates to signs, and more particularly to devices of this character of the illuminated type which are adapted to be mounted in locations where there is considerable danger of a person falling and being injured, such as in street car or motor bus entrances or exits.

One of the objects of the invention is to provide, in a manner as hereinafter set forth, 10 a sign of the aforementioned character, which is provided with warning indicia, which will be visible from several angles or sides, which may be mounted on any suitable support, such as are usually found in a public 15 passenger vehicle and which will not obstruct the entrance or exit in connection with which the sign is used.

Other objects of the invention are to provide an illuminated sign of the character set forth, 20 which will be simple in construction, strong, durable, efficient in its use, and which may be manufactured at a low cost.

Other objects and advantages of the invention will be apparent from a study of the 25 following specification, taken in connection with the accompanying drawings, wherein like reference characters designate corresponding parts throughout the several views, and wherein:

23 Figure 1 is a view showing the preferred embodiment of my invention, mounted in a street car at a point where the same will be visible to passengers either entering or leaving the same.

25 Figure 2 is a perspective view of an illuminated sign constructed in accordance with this invention.

Figure 3 is a vertical sectional view thereof.

40 Figure 4 is a view of a modified form of the invention, showing the same mounted in a step riser beneath the entrance, of a car or motor bus.

45 Figure 5 is a view in perspective of another modification of the invention, showing the same mounted on a vertical post.

Figure 6 is a view in perspective of the form of the sign illustrated in Figure 4.

Figure 7 is a rear elevation thereof.

50 Figure 8 is a horizontal sectional view of

the form of sign illustrated in Figures 4, 6, and 7.

Figure 9 is a horizontal sectional view of the form of the invention illustrated in Figures 1 and 2.

Referring to the drawings in detail, the reference character 1 designates generally a casing or housing including a rear vertical wall 2, an upwardly inclined top wall 3, a downwardly inclined bottom wall 4, a side wall 5, and a side wall 6, of less length than the side wall 5.

A panel supporting frame 7 is mounted on the forward portion of the bottom wall 4, in alignment with the side wall 6, from which wall said frame is spaced, as clearly shown in Figure 2 of the drawings. The frame 7 comprises a pair of right angularly extending channel members 8 and 9. At its lower end

10 the channel member or groove 8 extends rearwardly to the forward end of the side wall 6 and the channel member 9 is provided at its bottom end with a right angularly disposed extension which extends to the inturned flanged end on the forward edge of the wall

15 5. As shown in Figure 3, the walls 3, 4, and 5, may be provided with inturned flanges, such as 11, and instead of utilizing the right angularly disposed frame 7 an L-shaped angle iron may extend from the free corner of the bottom wall 4 to the corresponding corner of the top wall 3. Transparent sign elements 12 are

20 adapted to be slidably mounted between the forward end of the side wall 6 and the frame 7 and between the frame 7 and the wall 5, thus providing a sign which will be visible when viewed from either the front or side thereof. An incandescent bulb 13 is mounted

25 on the rear wall 2 in the casing 1, and is connected to a source of electrical energy. A pair of spaced superposed supporting rings or brackets 14, are mounted on the side wall 6 and adapted to clamp on any suitable support such as the vertical supporting post 15,

30 which is present in practically all public passenger vehicles.

It will thus be seen as illustrated in Figure 1, that passengers who may be leaving a vehicle, will almost invariably read the warning message carried by the illuminated sign,

as well as those passengers who are entering the vehicle from the street. In the form of the invention illustrated in Figure 4 of the drawings, a casing comprising a rear wall 16, 5 forwardly diverging end wall 17 and top and bottom walls 18 are provided, and the forward marginal portions of the wall 18 and one of the walls 17 are provided with inwardly turned flanges 19, for the reception of the re- 10 movable transparent indicia bearing panel or sign element 19. The other of the end walls 17 is provided with a bendable tongue 20, adapted to be secured about the end of the panel 19, when the same is in position in the 15 casing for preventing the accidental removal thereof. This form of the invention is adapted to be mounted in a riser 21 of a street car as shown in Figure 4 of the drawings.

In the form of the invention illustrated in 20 Figure 5, the substantially rectangular casing 22 is provided having inturned flanges 23 on the forward edges of the top, bottom and side walls thereof for removably securing the transparent sign 24 thereon. A pair of vertically spaced brackets 25 are mounted on the rear wall of the casing 22, and adapted to support the same on the vertical post or standard 26.

It is believed that the many advantages of 30 an illuminated sign constructed in accordance with this invention will be readily understood, and although the preferred form of the invention is as illustrated and described, it is to be understood that changes in the details of 35 construction may be had which will fall within the scope of the invention as claimed.

What is claimed is:

An illuminated sign comprising an open front lamp casing having a rear wall and top, 40 bottom, and side walls, one of said side walls of less length than the other, a transparent sign panel extending from the forward edge of the last named wall to the forward end of the top and bottom and the other side walls, 45 a transparent sign panel abutting the forward end of the first named panel and extending therefrom to the opposite side wall, a vertically disposed angular frame member connected, at its opposite ends, to the free 50 corners of the top and bottom walls of the lamp casing and adapted to engage the adjacent marginal edge portion of the sign panels and means for removably securing said panels in position.

55 In testimony whereof I affix my signature.
MILLARD M. KENNEDY.
